COMBINED PIANO AND TELEVISION RECEIVER

Webster E. Janssen, 32 Woodland Ave., Bronxville, N.Y.

Filed Feb. 17, 1964, Ser. No. 78,653

Term of patent 14 years

(Cl. D56—9)

FIG. 1

FIGURE 1 is a perspective view of a combined piano and television receiver showing my new design;

I claim:

The ornamental design for a combined piano and television receiver, substantially as shown and described.
